UNITED STATES PATENT OFFICE.

ALBERT J. ST. MARS, OF COLERAINE, MINNESOTA.

TUBE-SWAGE.

1,051,777.

Specification of Letters Patent. Patented Jan. 28, 1913.

Application filed July 22, 1911. Serial No. 639,903.

To all whom it may concern:

Be it known that I, ALBERT J. ST. MARS, a citizen of the United States, residing at Coleraine, in the county of Itasca and State 5 of Minnesota, have invented new and useful Improvements in Tube-Swages, of which the following is a specification.

This invention relates to swaging devices, and more particularly to devices for swaging the ends of tubes whereby the copper 10 ferrules may be readily placed thereon.

The object of the invention is the provision of a simple and efficient device of this character which may be placed beneath a 15 steam hammer and operated rapidly to swage a number of pipe ends within a short period of time.

Another object of the invention is the provision of a device of this character employing 20 separate die members which are adapted to be placed beneath and operated upon by a steam hammer and which, when released by the steam hammer, have means to automatically raise the upper die member 25 so that the tube may be conveniently removed and another tube placed in position to be operated upon.

Further objects of the invention will appear as the following specific description is 30 read in connection with the accompanying drawing which forms a part of this invention, and in which:—

Figure 1 is a front elevation. Fig. 2 is a rear elevation. Fig. 3 is a vertical sectional view. Fig. 4 is a similar view on the line 35 4—4 of Fig. 1.

Referring more particularly to the drawing, 1 and 2 represent respectively upper and lower die members each of which is 40 provided with transverse recesses 3 and 4 gradually decreasing in size from the front to the back of the dies, and being constructed substantially in semi-circular cross sectional form so that when the die members 45 are brought together the entire opening will be circular at all points throughout the width of the die members.

Secured to the back of the lower die member 1 is a plate 5 which slides over the upper 50 die member 2, and covers both the openings or recesses in said die members, and forms a limiting plate for the end of the tube, so that when the tube is inserted in

the die members it will abut against the plate 5 and thus be held in operative position 55 for the swaging operation.

In order that the members 1 and 2 may be properly guided one upon the other the upper die member is provided with vertical recesses 6 which are enlarged as at 7 for 60 a purpose to be hereinafter described. These recesses are arranged upon opposite sides of the recesses 3 and 4, and are adapted to receive guide pins 8 which are carried in the lower members in such position as to register 65 with the recesses 6. The lower die members are also provided with recesses 9, and seated in the recesses 9 and 7 and surrounding the pins are suitable expansion springs 10 which normally hold the die 70 members in separated relation, as shown, and which are adapted to be compressed by the action of the steam hammer when the latter is operated. This steam hammer has not been shown as it forms no portion of 75 this invention.

In the operation of the device the die members are placed with the lower one resting upon the anvil of the steam hammer and the upper one 2 arranged within the 80 path of the steam hammer so that as the same descends the member 2 is carried down until it rests upon the member 1. In the open position of the die members, the tube to be swaged is placed in the recesses 3 85 and 4 with its end lying against the limiting plate 5. The hammer is then operated and the die member 2 carried downwardly upon the die member 1. As the tube to be swaged is of substantially the same diameter 90 as the diameter of the recesses 3 and 4 at their front ends, and as the rear end of the recesses adjacent the plate is greatly reduced, the tube will be consequently reduced, swaged, or crimped upon a taper as 95 is readily understood.

Having thus described the invention, what I claim as new, is:

A tube swager comprising upper and lower identically constructed die members, 100 said members having their adjacent faces provided with enlarged communicating bores, and a small bore disposed above said enlarged bore of the upper member and below said enlarged bore of the lower member 105 and communicating therewith, the said large

and small bores providing an intermediate shoulder therebetween, guide pins having one end snugly fitted in said small bore of the lower member and extending within the 5 small bore of the other member, and springs encircling said pins and wholly disposed within the said enlarged communicating bores of the members, said springs bearing against

10 said shoulders and operating to hold said die members normally spaced.

In testimony whereof I affix my signature in presence of two witnesses.

ALBERT J. ST. MARS.

Witnesses:

G. E. O'CONNOR,

CAROLINE JOHNSON.
